FIG. 7.

UNITED STATES PATENT OFFICE

1,941,497

AUTOMATIC TRAIN CONTROL

Daniel Herbert Schweyer, Easton, Pa.

Application July 27, 1929. Serial No. 381,564

21 Claims. (Cl. 246—63)

The present invention relates to automatic train control, and aims to provide a novel apparatus for and method of transmitting signal impulses from the trackside to a moving train or vehicle.

The invention has for an object the provision of novel means for selectively energizing the track rails or other trackside elements with different frequencies of alternating or fluctuating electrical current or currents having different characteristics, for purpose of train control, depending on traffic conditions.

Another object is the provision of novel vehicle means for receiving the impulses from the track rails or other trackside elements and controlling a plurality of relays or other devices for controlling the train, operating signals, or performing other functions, in accordance with traffic conditions and the control of the trackside equipment.

With the foregoing and other objects in view, which will be apparent when the invention is more fully understood, the invention resides in the apparatus and method hereinafter described and claimed, it being understood that changes can be made within the scope of what is herein-after claimed within the spirit of the invention.

The invention is illustrated in the accompanying drawings, wherein—

Figure 1 is a diagrammatical view of one embodiment of the invention as applied on the vehicle.

Fig. 2 is a diagrammatical view of a portion of the vehicle equipment illustrating the use of electron tubes or valves.

Fig. 3 is a diagrammatical view of a portion of the track with a selective control for the track circuit.

Fig. 4 is a diagrammatical view illustrating trackside equipment including home and distant control relays.

Fig. 5 is a diagrammatical view illustrating the use of a polarized relay in the trackside equipment.

Fig. 6 is a diagrammatical view of another embodiment of trackside equipment.

Fig. 7 is a diagrammatical view illustrating still another embodiment of the trackside equipment.

Fig. 8 is a diagrammatical view illustrating a modification in the transformers shown in Fig. 7.

Referring to Fig. 3, the track circuit feed wires 13, 14, 15 and 16 are connected with sources of current, each having different characteristics,

as hereinafter referred to, and are connected, respectively, to switches 17 cooperable with contacts 18, switches 19 cooperable with contacts 20, switches 21 cooperable with contacts 22, and switches 23 cooperable with contacts 24. The contacts 18, 20, 22 and 24 are connected by wires 25 with the track rails or trackside elements 26, so that when any pair of switches is moved against the corresponding contacts, the rails or elements 26 will be energized with the corresponding current.

The switches 17, 19, 21 and 23 are controlled by the respective electromagnets A, B, C and D, the circuits of which may be controlled by suitable wayside circuits (not shown) which form no part of the present invention. In fact, the switches may be controlled by other means, either electrical, mechanical, pneumatic, manual, or the like, so that the switches 17 are closed for clear conditions, the switches 19 are closed and the switches 17 opened for a reduced speed, the switches 21 are closed and the switches 17 and 19 opened for a still lower speed restriction, and the switches 23 are closed and the other switches opened for a still further restriction in train speed.

The train or vehicle equipment includes a receiver 27 movable over the rails or elements 26 and including a core 28 extending transversely across said rails and having coils 29 thereon to receive pulsating current by induction from the rails 26.

The coils 29 are connected in additive relation in a circuit 30 which is connected by a transformer 31 with any suitable rectifier 32, the output terminals of which are connected to the primary of a transformer 33, a battery or other source of direct current 34 being preferably connected in the primary circuit.

Contacts 35, 36, 37, 38 and 39 engage the secondary of the transformer 33, and electromagnets a, b, c and d are connected across said contacts in succession, a rectifier 40 and condenser 41 being connected in the circuit of each electromagnet. Rectifiers 40 are asymmetric units permitting current to flow therethrough in one direction only. The condensers are used for tuning the circuits so that the respective electromagnets are energized by pulsating direct currents of the characteristic controlled by the corresponding relays A, B, C and D of the trackside equipment.

The relays a, b, c and d control the respective switches 42, 43, 44 and 45 or other suitable devices for controlling the brakes and speed con-

trol of a train, signals, or the like. The switches 42, 43, 44 and 45 may represent signal devices or may be taken to represent the controlling elements of suitable automatic mechanism for enforcing speed restrictions.

In operation, assuming the traffic conditions to be clear, the relay A is energized to close the switches 17, and the relays B, C and D are de-energized so that the switches 19, 21 and 23 are open, as seen in Fig. 3, current having the characteristic of circuit 13 is impressed from the wires 25 into the track rails or trackside elements 26, which current will be picked up by the receiver 27 and transmitted through the transformer 31, rectifier 32 and transformer 33.

This will affect the relay a so that it picks up or closes the switch 42, thereby providing clear conditions on the vehicle, and the switches or elements 43, 44 and 45 remaining down.

20 Under different speed restrictions, one of the relays B, C, D is energized with the remaining trackside relays deenergized, so as to connect the corresponding circuit 14, 15 or 16 with the track rails 26, thereby impressing current of corresponding characteristic thereon, and same being picked up by the receiver 27 will result in the corresponding relay b, c or d being energized to lift the corresponding switch or element.

Under danger conditions, all of the trackside 30 relays are deenergized, thereby deenergizing the rails 26, so that the vehicle equipment does not receive energy from the rails, and all of the vehicle electromagnets or relays a, b, c and d will be deenergized, thereby establishing danger conditions on the vehicle.

Various conditions may thus be selectively transmitted by electrical impulses having particular characteristics to the track rails or trackside elements and thence by induction to the vehicle equipment which controls the relays a, b, c and d selectively. There need be no moving parts in either the trackside or the vehicle equipment aside from the switches. Consequently, the apparatus is simple in construction and installation, and maintenance cost is materially reduced as compared with systems requiring motor driven mechanism and other moving parts requiring periodic attention.

50 The use of a tuning condenser in series with the secondary of a transformer and a control relay, as used for the relays a, b, c and d, is disclosed in my Patent No. 1,342,873, granted June 8, 1920, and the use of pulsating direct current between the trackside and vehicle equipments is disclosed in my application Serial No. 301,021, filed Aug. 21, 1928.

Fig. 2 illustrates the use of a pair of electron tubes or valves 32a between the wires 30a connected to the receiver and the transformer 33a. 60 The plates 50 of said valves are connected to one terminal of the primary, and the other terminal of said primary is connected to the filaments 51 of said valves in series with a battery 52 or other source of direct current. One wire 30a is connected to the grid 53 of one valve and to the filament of the other valve, and the other wire 30a is connected to the filament of the first named valve and to the grid of the second named valve. The valves thus serve as a double wave rectifier, 70 each valve permitting one-half of a wave to pass through, so that the primary of the transformer is energized by pulsating direct current of the same frequency as is the circuit of the wires 30a.

Fig. 4 illustrates a means for connecting the wires 13c and 14c with the wires 25c leading to

the rails or trackside elements. Relays H and D, respectively, are provided. When the H relay is energized it raises the switches 17c against contacts 18c to connect the wires 13c and 25c. When the D relay is energized the switches 19c are raised against contacts 20c, and switches 17c of the H relay are dropped when this relay is deenergized against contacts 18x, thereby connecting the wires 14c with the wires 25c through the switches 19c, contacts 20c, contacts 18x, and switches 17x, the switches 17c being removed from the contacts 18c.

80 Fig. 5 illustrates the use of a trackside polarized relay, having the neutral switches 17d and the polarized switches 19d. When current flows in one direction through the relay, the switches 19d engage contacts to which the wires 13d are connected, to connect said wires through said contacts and switches with the switches 17d engaging contacts to which the wires 25d are connected. When the current flows in the opposite direction through the relay, the switches 19d move against contacts to which the wires 14d are connected, thereby connecting said wires 14d with the wires 25d. The switches 17d drop open 100 when the relay is deenergized to disconnect the wires 25d from either of the wires 13d or 14d.

90 Fig. 6 illustrates a trackside equipment wherein in the line wires 1e simultaneously carry different cycles or frequencies of fluctuating current 105 which are selectively transmitted by a transformer 2e to transformers 4e, 6e and 8e, the primaries of which are connected in tuned circuits with the secondary of the transformer 2e, so that the secondaries of the transformers 4e, 6e and 8e 110 are energized individually by the separate cycles or frequencies of fluctuating current. For example, if currents of 6, 3 and 1½ cycles are impressed on the line wires 1e, the transformer 4e may be tuned to 6 cycle current, the transformer 115 6e for 3 cycle current, and the transformer 8e for 1½ cycle current.

95 The secondaries of the transformers 4e, 6e and 8e are connected through switches 17e, 19e and 21e with the wires 25e that are connected to the 120 rails or trackside elements 26e. The switches are controlled by the respective electromagnets A, B and C, or by other suitable means, so that when the switch 17e is closed, such as for clear 125 conditions, 6 cycle current is transmitted to the rails 26e, whereas if the switch 19e is closed then 3 cycle current is transmitted to the rails, and when the switch 21e is closed then 1½ cycle current is transmitted to said rails.

130 The equipment shown in Fig. 6 serves to segregate the currents of different cycles or frequencies and to selectively transmit the segregated currents to the rails or trackside elements. The arrangement shown in Fig. 7 uses a single current of a specified cycle or frequency and develops currents of different characteristics for selectively energizing the rails or trackside elements.

135 Fig. 7 illustrates still another variation in the trackside equipment, in which a source of fluctuating current of a predetermined cycle or frequency is stepped up to provide currents of higher cycles or frequencies.

140 The line wires 1f are supplied with alternating or fluctuating current of low cycle, which is transmitted through a transformer 2f, having two secondary windings, to the circuits 3f and 60 each including one of the secondary windings.

145 The circuit 3f includes primary windings of a pair of transformers 4f, said primary windings 150

being connected in series, and the secondary windings of said pair of transformers are connected in series in the circuit 5f which includes in series the primary windings of a second pair 5 of transformers 6f. The secondary windings of the transformers 6f are connected in series in a circuit 7f which has connected in series therein the primary windings of a pair of transformers 8f, and the secondary windings of the last 10 named transformers are in turn connected in series in a circuit 9f including in series, the primary windings of a fourth pair of transformers 10f.

Each transformer, as shown, comprises a 15 closed circuit core on which the windings are disposed, the primary windings being shown at the top and the secondary windings at the bottom of the cores.

Each of the circuits 3f, 5f, 7f and 9f includes 20 an adjustable condenser 12f for tuning the circuit, such condensers being used to correct the power factor.

The lead off wires 13f, 14f and 15f are connected to the circuits 5f, 7f and 9f, respectively, 25 between the pairs of secondary and primary windings of the successive transformers, so that currents of different cycles may be taken from the several circuits and transmitted to the rails or trackside elements 26f, the switches 17f, 19f and 21f and their contacts 18f, 20f and 22f connecting the wires 13f, 14f and 15f selectively with the wires 25f under the control of the electromagnets A, B and C.

The circuit 60 includes full-wave rectifying 30 means 61 so as to provide for unidirectional current in said circuit, and windings 62 are provided on the transformers and are connected in multiple or parallel to the circuit 60, so as to impress unidirectional magnetic flux in the cores of the 40 transformers. It will be noted that the windings of each pair of transformers are connected in series.

The windings are all in the same direction with respect to the flow of magnetic flux in the cores, 45 excepting that one secondary winding of each pair is wound reversely. As a result, the series of transformers and their circuits produce a cascade action in increasing the cycle or frequency of current in the successive circuits 5f, 7f and 9f, 50 under the principle of known frequency doublers.

The alternating magnetic flux induced into the cores of each pair of transformers, together with the action of the magnetic flux produced in the cores by the windings 62, will induce 55 through the opposed secondary windings a fluctuating current of double the cycle or frequency. Second harmonics are produced that double the cycle or frequency of the current in passing from each circuit to the next, and consequently the 60 circuits 5f, 7f and 9f are energized by fluctuating currents of increased or doubled cycles in succession.

For example, if the line wires 1f receive $\frac{3}{4}$ cycle current, then the circuit 5f is energized by 65 current of $1\frac{1}{2}$ cycle, the circuit 7f by 3 cycle current and the circuit 9f by 6 cycle current.

The currents of different cycles or frequencies may thus be selectively transmitted to the track 70 rails or trackside elements 26f in the same manner as described in connection with Fig. 3, through the relays A, B and C. The circuits 13f, 14f, and 15f, correspond with circuits 13, 14 and 15, Fig. 3, respectively.

Fig. 8 illustrates a modification in the 75 transformers used in the hook-up shown in Fig. 7.

in that the core has a cross yoke between the primary and secondary windings on which the winding 62a of the unidirectional or direct current is disposed, the effect being the same.

Having thus described the invention, what is 80 claimed as new is:

1. The method of energizing trackside train control elements consisting in continuously generating from a single source, at least three currents of different frequencies obtained one from the other, and selectively transmitting a single one of such currents to said elements and disconnecting the other currents from said elements. 85

2. The method of energizing trackside train control elements consisting in continuously generating, from a single source, a series of more than two currents of progressive frequencies obtained one from the other, and selectively transmitting but one of such currents to said elements. 90

3. The method of energizing trackside train control elements consisting in continuously generating, from a single source, a series of more than two currents obtained one from the other which from each current to the next is doubled in frequency, and selectively transmitting a single 100 one of such currents at a time to said elements.

4. The method of energizing trackside train control elements consisting in continuously generating, from a single source, by induction and inductive control a series of more than two currents of progressive frequencies obtained one from the other, and selectively transmitting a single one of such currents at a time to said elements. 105

5. Train control apparatus comprising track- 110 side elements, means for continuously generating, from a single source, at least three currents of different frequencies obtained one from the other, and means for selectively transmitting such currents one at a time to said elements. 115

6. Train control apparatus comprising track- 120 side elements, means for continuously generating, from a single source, a series of more than two currents of progressive frequencies obtained one from the other, and means for selectively transmitting such currents one at a time to said elements.

7. Train control apparatus comprising track- 125 side elements, means for continuously generating, from a single source, a series of currents obtained one from the other each of which is double the frequency of another one, and selectively transmitting such currents to said elements always in the same relative polarity.

8. Train control apparatus comprising track- 130 side elements, means for continuously generating, from a single source, by induction and inductive control a series of currents of progressive frequencies obtained one from the other, and means for selectively transmitting said currents to said elements always in the same relative polarity. 135

9. Train control apparatus comprising track- 140 side elements, a single source of fluctuating current, a series of more than two circuits inductively connected with said source and having means for controlling the frequency of currents therein so that such circuits are energized by currents of different frequencies, means for selectively connecting said circuits with said elements and vehicle carried elements each responsive to 145 one of said frequencies alone.

10. Train control apparatus comprising track- 150 side elements, a single source of fluctuating current, a plurality of circuits inductively connected with one another and with said source, a rectifier

controlling the frequencies of currents in said circuits so that said circuits are energized by currents of progressive frequencies, and means for selectively connecting said circuits one at a time with said elements.

11. Train control apparatus comprising track-side elements, a single source of fluctuating current, a plurality of circuits, transformers inductively connecting said circuits in cascade with said source, a rectifier in the circuit of one of said transformers controlling the frequencies of currents in said circuits so that said circuits are energized by currents of different frequencies, and means for selectively connecting said circuits with said elements.

12. The method of transmitting control influences from the trackside to a moving vehicle consisting in continuously generating, from a single source, at least three currents of different frequencies obtained one from the other, selectively transmitting said currents one at a time to trackside elements, picking up on a vehicle the current from said elements, and selectively controlling a plurality of vehicle devices from the individual picked up currents.

13. Train control apparatus comprising track-side elements, means for continuously generating, from a single source, at least three currents of different frequencies obtained one from the other, means for selectively transmitting said currents one at a time to said elements, pick-up means on a vehicle cooperable with said elements for receiving the different currents therefrom, a plurality of vehicle devices, and means selectively controlling said devices from said pick-up means according to individual currents of different frequencies.

14. Train control apparatus for a single block comprising trackside elements, a source of fluctuating current, a series of more than two circuits, transformers inductively connecting said circuits in series with said source, a rectifier in the circuit of one of said transformers, and means for selectively connecting said circuits with said elements.

15. Train control apparatus for a single block comprising trackside elements, a source of fluctuating current, a series of more than two circuits, transformers inductively connecting said circuits in series with said source, means influencing said transformers for doubling the frequencies of the currents in said circuits in succession, and means for selectively connecting said circuits one at a time with said elements.

16. In a system for energizing a track circuit, the combination, a pair of transformers, a primary coil on each transformer, a circuit connecting said primary coils in series with a source of energy, a secondary coil on each of said transformers, a secondary circuit connecting said coils with the track circuit in series with a condenser, a third

coil on each of said transformers and a circuit connecting said third coil to an A. C. supply through a rectifier.

17. In a system for energizing a track circuit, the combination, a transformer having a primary coil and a secondary coil, a circuit connecting said primary coil with a source of energy, a circuit connecting said secondary coil with a condenser and with the track circuit, a third coil on said transformer and a circuit connecting said third coil to an A. C. supply through a rectifier. 80

18. In a system for energizing a track circuit, the combination, a transformer having an input circuit with a primary coil and an output circuit with a secondary coil, a circuit connecting said primary coil with a source of energy, a circuit connecting said secondary coil with the track circuit and a third coil inductively coupled on said transformer with the other coils and connected in a circuit energized from an A. C. supply through a rectifier. 90

19. In a system for energizing a track circuit, the combination, a pair of transformers, each having a primary coil and a secondary coil, a circuit connecting said primary coils with a source of energy, a secondary circuit connecting said secondary coils with the track circuit and another coil on each of said transformers inductively coupled with the primary and secondary coils and connected in a circuit energized from an A. C. supply through a rectifier. 100

20. In a system for energizing a track circuit, the combination, a single source of current, a pair of secondary coils energized from said source, a plurality of transformer yokes, each having a primary and a secondary coil, the primary of the first yoke being energized from one of said secondary coils and the primary of the second yoke being energized from the secondary of the first yoke and the primary of the third yoke being energized from the secondary of the second yoke, a third coil on each of said yokes, a rectifier in the circuit of the other secondary coil and said circuit energizing said third coils and connections for energizing the track circuit connected to the secondary coil of each yoke. 110

21. In a system for energizing a track circuit, the combination, a single source of current, a pair of coils energized from said source, two groups of transformer yokes each connected in cascade, with the secondary of one energizing the primary of the next and the primary of the first transformers of each group energized by one of said coils, a third coil on each of said transformers, a circuit for energizing said third coils including a rectifier and energized by the other of said pair of coils and connections for energizing the track circuit connected to the secondary coil of each transformer. 125

DANIEL HERBERT SCHWEYER. 133
